APPARATUS FOR WEAVING FABRICS.

1,080,298.

Specification of Letters Patent.

Patented Dec. 2, 1913.

Application filed August 21, 1913. Serial No. 785,833.

To all whom it may concern:

Be it known that I, EMIL PREIN, subject of the King of Prussia, and resident at Hanover; in the Province of Hanover, Kingdom of Prussia, German Empire, have invented certain new and useful Improvements in Apparatus for Weaving Fabrics, of which the following is a specification.

This invention relates to apparatus for 10 the weaving of fabrics, in which the filaments all lie close to the yarn.

During the process of weaving, there are 15 always filaments which spread out from the yarn, as is well known, even when they have been previously held fast or previously prepared, or when the weaving takes place in the moist state, and this especially happens 20 with the filaments of the warp yarn in consequence of the mutual friction of the filaments during the forming of the shed and in consequence of the up-and-down motion of the reed blade, and also with the filaments of the weft yarn in consequence of the suddenly occurring cessation of the adhesion 25 of the filaments during the shooting and rapid running out of the yarn and also in consequence of the attraction between the material which is running out and that which remains behind. A portion of these 30 filaments which are set free are bent, folded over and pressed down in the fabric by the motion of the reed during the throwing of the weft thread and owing to the threads lying over it in the interweaving. The 35 filaments which still project from the fabric are subsequently removed by shearing and singeing machines in order to render the fabric suitable for its various purposes. But by this process not only are a number of 40 filaments which possess a great power of resistance to breakage, lost for the fabric, but the interweaving of the filaments which project and the forcible removal of the projecting filaments have also very serious 45 drawbacks. The objection to the shearing is that the very sharp knives operating at a great speed not only shear off the projecting filaments but also, any knots and threads which stick out and cut them clean away.

50 which is at first not noticed as damage and is only discovered on the application of tests for strength, whereupon one and the same fabric will give uneven results. With the singeing process, the repeated sudden heat

makes all the woven filaments especially the 55 unicellular cotton filaments brittle.

It is a great drawback moreover that the bent and folded interwoven fibers are held in the fabric with their power of projection unweakened. If then at a later stage, the 60 fabric is treated for some technical purpose, these filaments always again occur as points escaping out of the fabric, because their power of projection and the adhesive power of the preparation act against each other. 65 Also, when the bent fibers are held during the drying under mechanical pressure, which as is well known is effected in various manners in technical weaving according to the application of the goods, they lie only 70 restrained but not cured. They hereafter also gradually free themselves from the bedding by reason of the various movements of the material, the alternative effects of temperature and of unequal wear, whereby 75 much damage are caused.

The object of the present invention is a mechanism, shown in various modifications, which is intended to obviate the above mentioned drawbacks. By means of this mechanism, the warp threads are smoothed flat immediately at the weaving point by a suitable means in the moist condition in such a way, that the projecting fibers are arranged lengthwise against the threads, and 80 are woven into the fabric in this position. Moreover, it is of especial importance that the application of the fibers to the yarn should take place just there and at that moment when forces tending to release the 85 fibers can no longer act upon the threads. As a suitable material for the moistening body, a rubber sponge is preferably made use of.

The invention comprises an arrangement 95 whereby the support for the moistening body is attached to the loom shed so as to be capable of moving up and down and participate in its to-and-fro motion.

The device itself can be constructed in 100 various forms.

In the accompanying drawing some of these forms are illustrated as follows:—

Figure 1 shows an elevation of the first construction in combination with the adjacent parts of the loom. The drawing shows the frame of the moistening body 105 and the mechanism for moving it just be-

fore the application of the moistening body. Fig. 2 shows the same device in the position after the application of the moistening body and during the moistening.

5 In all these figures, *a* indicates the lay sword, *b* the lay, *c* the reed, *d* the breast plate of the loom. The warp threads are indicated by *n* and the finished fabric by *o*.

10 The moistening body composed of spongy rubber or the like rests in a long liquid container *e* which extends over the entire width of the fabric and possesses above a slot for the exit of the moistening body. The liquid container *e* is removably attached to the 15 part *b* and swings with it to and fro. By the arrangement of the moistening body on the aforesaid part *b* there is effected a specially favorable stroking action and the possibility of the easy arrangement of the separate parts of the movement is assured. The 20 moving and guidance of the moistening body and its holder is effected by means of suitable rods and levers under the influence of the motion of the part *b*. At one end of the 25 container is a tubular support *f* to which by means of a tube the apparatus can be connected to a filling receptacle.

30 In the constructional form illustrated in Figs. 1 and 2, the container *e* is detachably secured to a bar *g*, which possesses projections *h* in the neighborhood of each end, to which projections, two pivoted unequally long levers *i* and *k* engage, whereby the bar is connected to the loom. For effecting of 35 this connection there are provided on each side under the part *b* projecting lugs *m*. The pressing of the moistening body at the point of weaving is effected by means of a catch lever *q*, which slips over a fixed boss *r*. The catch lever *q* engages by means of a projection *p* under the part *i* and thereby effects 40 the raising thereof when the catch slips over the boss *r* (Fig. 2). The boss *r* is placed adjustably upon a fixed holder *e* and 45 is so arranged that the moistening body engages the lower plane of the warp substantially at the fell. In consequence of the unequal lengths of the levers *i* and *k* there results on the raising of the moistening body 50 a short backward motion thereof in regard to the part *b*. The consequence of this is that on the simultaneous motion of the part *b* the moistening body at the weaving point stands still for a short moment. This causes 55 the moisture therefrom to penetrate more effectively in the warp threads and to moisten these completely. Hereby a better laying down of the fibers on the threads is effected. According to the length of the 60 adjustable boss *r* the period of contact can be adjusted at will. As soon as the catch *q* has passed over the boss *r* it slides off it and allows the limb *i* together with the bar

g and the liquid container *e* with the moistening body to fall down. In order to hasten this rearward motion there is provided a spring *t*. In order to prevent any lifting of the fabric on the engagement of the moistening body there is placed above the fabric throughout its whole length a lath *u* which is held by the holders *v*. The moistening of the completed fabric is prevented by a protective band *w* which is stretched beneath the fabric close up to the fell, and is secured at both sides as well as behind in a suitable manner.

Having now described my invention and in what manner the same is to be used, what I claim and desire to secure, is—

1. The combination with a loom having 80 a lay, of moistening means guided thereon, an arm pivoted on the lay and having operative connection with said moistening means, and a stop on the loom frame to engage the 85 said arm to cause the moistening means to be raised on the backward movement of the lay.

2. The combination with a loom having a lay, of a bracket carried by said lay, a pair 90 of links pivoted to said bracket, one of said links being longer than the other, a moistening device pivoted to said links, an arm pivoted on the bracket and having a projection engaging one of the links and a stop in the path of the free end of said arm 95 adapted to engage the arm as the lay oscillates and thereby oscillate said moistening device.

3. In apparatus of the character described, a loom frame, a boss adjustably fixed on 100 said frame, a catch-lever adapted to move over said boss, a lug on said catch-lever, an arm engaged by said lug, a moisture holder engaged by said arm, a link connecting the lower part of said moisture 105 holder to a block, and a spring drawing said container downward whereby said moisture holder is reciprocated into and out of contact with the threads at the weaving point.

4. In apparatus of the character described, and having a moistening body just below the weaving point, a protective band to prevent contact of the moistening body and the fabric.

5. In apparatus of the character described and having a moistening body, a bar disposed as a counter holder for the adjustment of said moistening body.

In testimony, whereof I have signed my 120 name to, this specification in the presence of two subscribing witnesses.

EMIL PREIN.
